UNITED STATES PATENT OFFICE

2,480,812

INFANT'S TOILET SEAT ATTACHMENT

Gertrude A. Muller, Fort Wayne, Ind., assignor
to The Toidey Company, Gertrude A. Muller,
Inc., a corporation of Indiana

Application November 13, 1945, Serial No. 628,276

5 Claims. (Cl. 155—31)

1

This invention relates to improvements in an infant's toilet seat attachment for use on an adult toilet seat of usual structure.

An object of the invention is to provide an infant's toilet seat having a folding back-rest and side-arms and an adjustable foot-rest having locking engagement with the supports for the side arms when the foot-rest is moved to a selected position and the back-rest and side-arms are secured in their unfolded position.

And another object of the invention is to so arrange the folding and adjustable parts as to permit collapse of the parts into compact form to facilitate transport and storage of the appliance when not in use.

Other objects and advantages of the invention appear in the following description.

An illustrative embodiment of the invention is shown in the accompanying drawings, in which:

Fig. 1 is a perspective view of an appliance in which the invention is incorporated, the back-rest and side-arms being secured in unfolded position and the foot-rest extended and locked in a selected position;

Fig. 2 is a side elevational view of the appliance when collapsed and showing the folding and adjustable parts dotted in position for use; and

Fig. 3 is a fragmentary detail perspective view of one of the side-arm supports and the locking lug thereon.

The illustrative embodiment of the invention consists of a seat 4 having a seat opening 5 therein of the usual form, a back-rest 6 having end supports 7 rigidly secured thereto and which extend astride of the seat to which the end supports are pivotally secured by means of screws 8, a spring brace 9 on the back-rest that has locking engagement with a stud 10 on the rear end of the seat by which to secure the back-rest in unfolded position, side-arms 11 secured to the back-rest by means of screws 12 provided with forward arm supports 13, and a foot-rest 14 provided with extension bars 15 that lie astride the seat 4 against the sides thereof to which they are movably secured by means of screws 16 that project through the slotted bars and on which the slotted bars have longitudinal sliding movement.

The forward arm supports 13 are pivotally secured at one of their ends to the corresponding side-arms 11 adjacent the forward ends thereof, by means of screws 17, and the opposite ends thereof are pivotally secured to the seat by means of screws 18 that project through the elongated slots 19 in the corresponding extension bars 15. The lower ends of said forward arm supports 13

2

are each provided with an inturned lock lug 20 that is adapted to have engagement in one of a series of notches 21 made in the lower edge of each extension bar 15 when the foot-rest is in a selected position and the back-rest and side-arms are moved into opened position and secured in such position by engagement of the spring brace 9 with the stud 10.

Preferably, there are provided washers 22 that are disposed between the heads of the screws 16 and the outer faces of the extension bars 15 that are held loosely in place so the extension bars may readily be moved longitudinally without binding.

15 In operation, the back-rest and side arms are partially raised from their folded position by manipulating the back-rest, whereupon the lock-lugs 20 on the forward supports for the side-arms are automatically moved from their engagement with the extension bars, thus permitting the foot-rest to be moved forwardly to a selected position. The back-rest together with the side arms are moved into their full unfolded position where they are held by engagement of the spring brace 9 with the stud on the back end of the seat, and the lock-lugs 20 are moved into the adjacent notches 21 in the extension bars thus securing the foot-rest in the selected position. The appliance is collapsed by releasing the spring brace from the stud and then moving the folding and adjustable parts into their initial folded positions.

Variations from the particular construction above disclosed may be resorted to by the exercise of skill in the art, without departure from the spirit or scope of the invention.

What I claim is:

1. An infant's toilet seat attachment consisting of a seat having an opening therein, a folding back-rest having end supports rigidly secured thereto and which extend astride of said seat and are pivoted thereto, a spring brace on said back-rest having locking engagement with a stud on the rear end of the seat by which to secure the back-rest in unfolded position, side-arms pivoted at one of their ends to the back-rest and having in pivotal connection with their opposite ends forward arm supports that have pivotal connection with said seat, the lower ends of said forward arm supports having on their lower ends inturned lock-lugs respectively, and a foot-rest provided with slotted extension bars that lie astride said seat against the sides thereof, supports on the seat extending through the slots in said bars on which said bars have longitudinal

guided sliding movement, each extension bar having a series of notches in which said lock-lugs have engagement accordingly as said foot-rest is adjusted to a selected position and the back-rest and side-arms are moved to their full unfolded position, thus to secure the foot-rest in the selected position.

2. An infant's toilet appliance consisting of a seat having an opening therein, a folding back-rest having pivotal support on said seat and provided with means for locking the back-rest in its unfolded position, side-arms having pivotal connections at one of their ends with said back-rest, forward arm supports for the opposite ends of said side-arms pivotally connected thereto at one of their ends and with said seat at their opposite ends, each of said forward arm supports having an inturned lock-lug, a foot-rest provided with extension bars that lie astride said seat along the sides thereof, and supports on the seat upon which said extension bars have longitudinal guided sliding movement, said lock-lugs having engagement with said extension bars when the back-rest and side-arms are secured in their unfolded positions whereby the foot-rest is held in a selected position of adjustment.

3. In an infant's toilet appliance of the type that has a toilet seat provided with a folding structure pivotally supported thereon constituting a back-rest and side-arms, means for securing the folding structure in unfolded position, a foot-rest including extension bars that are disposed astride said seat, and overlap the sides thereof, each extension bar having an elongated slot, a pair of guide-screws on the seat, spaced apart from each other, that extend through the slot of the corresponding extension bar on which said bars are longitudinally adjustable, and means on said folding structure engageable with said extension bars when the folding structure is

moved into unfolded position whereby to secure said foot-rest in a selected position of adjustment.

4. In an infant's toilet appliance in which a toilet seat is provided with a folding structure pivotally supported thereon, constituting a back-rest and side-arms, and provided with means to lock the structure in unfolded position, a foot-rest provided with extension bars, supports on the seat on which said bars have longitudinal guided sliding movement and locking means consisting of lugs on the folding structure and notches in said extension bars that have engagement when said appliance is unfolded whereby to secure the foot-rest in a selected position relative to the seat.

5. In an infant's toilet appliance consisting of a toilet seat, a folding structure on said seat provided with latching means to hold the folding structure in unfolded position, extension bars supported on guides on said seat and provided with a foot-rest, and a locking means on the folding structure having engagement with said extension bars when the folding structure is moved into unfolded position.
